SHUTTLE BRUSH AND HOLDER

John A. Matson, Troy, N. H.

Application May 16, 1950, Serial No. 162,183

4 Claims. (Cl. 139—218)

1

This invention relates to shuttles, especially to those used in weaving woolen yarn or other similar yarn which carries along a certain amount of short fibre or fuzz which may get into the shuttle eye and clog it and for any other shuttles where a gentle tension or holding back on the yarn is desirable.

In the past, and in addition to the various types of friction pads in the shuttle eye and fur which engages the yarn mass on the bobbin, bristle brushes extending into the bobbin chamber in position to intercept the thread have been extensively used.

The usual method of positioning these brushes is to bore a hole through the side of the shuttle leading into the bobbin chamber and then force a bunch of bristles into this hole either smearing the inside of the hole or the outside of the bristles with adhesive so that they stay in position.

When the bristles wear down and it is necessary to replace them, it is a difficult task to clear the hole of bristles and adhesive and to do a good job, the shuttle must be taken out of service into a properly equipped shop.

This device is a clamp and is an improvement on the device shown in my patent of March 20, 1945, No. 2,371,701, and includes a receiving member which goes into a suitable brush hole extending in from the outer face of a side wall of a shuttle and which has a countersunk head recess in the outer face which forms an annular shoulder with a smaller sized shank hole which is smooth on its curved surface and extends through that side wall, the receiving member having a head seated in the head recess and an inwardly projecting tubular shank seated in the shank hole, smooth on the outside, and having a dead end hole with interior threads, together with a brush holding member which has a head on the inside of the side wall and a shank with outside threads to engage the inside threads in the receiving member shank and which carries a bunch of bristles. The receiving member may be preferably of some suitable plastic such as poly-styrene but might be of metal, but the brush holding member is preferably made of a thermo-plastic such as poly-styrene into which a bunch of bristles is permanently fastened.

When the bristles of the bristle holder wear down, they with their holder can be thrown away and replaced by another similar holder or both the receiving and holding member can be thrown away.

The entire brush includes a bunch of bristles held by a brush holding member having a head to engage the inner face of a shuttle side wall

2

and a shank with outside threads to engage the inside threads of a tubular shank of a receiving member having a head to engage the part of the outer face of the same shuttle side wall represented by the countersunk head recess part of the brush hole.

The receiving member can be made without a tubular shank, but with a shank hole in the head with inside threads.

Preferably the receiving member can be used again, but the brush holding member cannot be reused.

Preferably I use bristles made of nylon or some suitable similar cellulose-acetate plastic, bent and formed in the plastic bristle holding member when it is being formed, both being set together while the plastic is soft in any conventional injection mold machine, the bristles being bent to form a loop into which the plastic is forced.

However, I can use a brush holding member in which straight bristles such as hog bristles, not bent, are held in place as by being fastened in by means of an adhesive.

I find that bristles of nylon or some similar material will wear many times as long as hog bristles and in my preferred form of device, I use such synthetic bristles which have been cut to twice the desired length, then bent in the middle and set permanently in the bristle holder.

The receiving member may be made of a light metal such as aluminum, or magnesium and should be turnable while the brush holding member can be provided with flat edges, pin holes, a washer or with a roughened inner face of its head to prevent turning, while the clamp members are being screwed together.

This device is an improvement on my Patent No. 2,371,701 because that shows a three part device comprising expendable "removable bristles" with a bend, held by thread, passed through a hole in a bristle holding member in such a way that when such member is screwed together with a receiving member the bend in the bristles is expanded and the bristles are held in place; while this is a two part device, one part being expandable, the parts being clamped together through the wall of a shuttle with the bristles at any desired angle with the thread.

In the drawings,

Fig. 1 is a plan view of the eye end of a shuttle with my device in place.

Fig. 2 is an elevation from the side of the shuttle eye of the same shuttle shown in Fig. 1, part of the wall being broken away to show a brush in the opposite interior wall.

Fig. 3 is an elevation of the brush holding mem-

ber and Fig. 4 is an elevation of the receiving member.

Fig. 5 is a sectional view through part of a shuttle wall and through the receiving member, and the brush holding member, as in Figs. 3 and 6.

Fig. 6 is a plan view of the top or head of a brush holding member of the type shown in Figs. 1 to 5.

Fig. 7 is a view of the bottom or shank end of a brush holding member with a disk shaped head.

Fig. 8 is a plan view or top view of a brush holding member with a disk shaped head with pin holes.

Fig. 9 is a section on a plane which runs through the axis of a brush holding member of a modification of the type shown in Fig. 5.

Fig. 10 is a view, partly in section, on a plane which runs through the axis of a receiving member of a type somewhat different from that shown in Fig. 4.

Fig. 11 is a side elevation of a modified form of brush holding member.

In the drawings S represents a shuttle in which is a bobbin chamber 40 in which is positioned the bobbin B with its tip 3 near the front of the bobbin chamber and near the shuttle eye E, which we will call the outer end of the shuttle. D represents the thread.

The side walls of the bobbin chamber 40 are indicated by 41 and 42, while the outer face of side 42 is indicated by 49 and the inner face by 48, while 44 is what is known as the thread groove in which the thread runs when the shuttle is travelling in a loom towards the outside of the loom, as distinguished from the inside.

H represents a bristle brush unit of which there may be one or two on each side, each positioned in a brush hole G and each having a bunch of bristles indicated by P.

As shown in Fig. 5, these bristles are bent in the middle at 7 and tied together at 8 with a string of a suitable kind. The brush hole G has extending in from the outer face 49 a brush hole head recess 17 which forms an annular shoulder 46 with a face 45 and there is a smaller shank bore part 15 which extends through to the inner side 48 and which has a smooth curved surface 16. The head recess 17 is cylindrical and has a smooth curved face 11.

F represents a receiving member with a disk-shaped head 60, smooth on its curved face 61 to fit not too closely in the head recess 17. It has a turning slot 67 whereby it can be turned by a screw driver and its inner face 63 rests against the face 45 of the recess, there being also an integral tubular shank 62 which is smooth on its outside 68 to fit into the bore part 15. This shank is of tubular form and has a dead end hole 64 with interior screw threads 65.

However the shank can be omitted as shown in Fig. 10.

M is a brush holding member which includes a head 1 shown as having a flat face 6 to engage the inside face 48 of the shuttle side and a shank 2 having outside threads 4 which engage the inside threads 65 of the tubular shank 62. This shank 2 is of such length that its end 13, preferably, does not quite reach the dead end 64.

As shown in Fig. 6, the head M has two flat sides 36, 38, and is bevelled at its curved ends 5, 5. This brush holding member M is preferably made of a suitable plastic into which the bunch of bristles P can be molded when the member M is being formed. Preferably these

bristles P are tied at 8 but there is a loop left at 7 which is filled with the plastic during the molding and setting operation.

This bunch of bristles P may be set at an angle with the bristle holding member head 1 and in such a way that they can be directed down and outward or up and outward, depending on whether or not they are to go under the bobbin or over the bobbin.

The bristle holding member M with bristles P is put in the right position on the inner face of a side in a desired direction and may be then held in that position between fingers while the receiving member such as F is turned as with a screw driver in slot 67 until the head 63 is forced up against the face 45 of annular shoulder 46 and the face 6 of brush holding member M presses up tight against the inner face 45.

In Fig. 7, I show a brush holding member such as N with a face 50 similar to face 6. This face 50 is formed with ridges 51, 54, which help to prevent it from turning as the receiving member is screwed onto the threaded shank 52, thus pressing ridges 51 into the wood. Figs. 7, 8, and 9 show a round or disk shaped head.

As shown in Fig. 8, I may use a brush holding member head R which is bevelled at 25 and has two holes 28, 26 into which a pin or pins of a suitable tool or wrench can be inserted to keep it from turning.

In Fig. 9, is shown a brush holding member A which may be of plastic or may be of some other suitable material, provided with a bristle hole 82 into which a brush B of straight bristles 81 can be inserted and held in place as by an adhesive 83, which preferably surrounds each bristle so as to keep the whole firmly in place.

Z represents a light adhesive or a washer which may be of rubber or other suitable friction material to keep the head of the brush holding member from turning with the receiving member especially when separating the brush holding member therefrom to throw it away. A washer W Fig. 10 can be used inside the receiving member head in case the head recess is bored too deep.

In Fig. 10 is shown a construction in which there is a head recess 72 into which is seated a receiving member K which consists entirely of what might be called a head 73 or a combination head and shank. This receiving member is provided with a dead end hole having interior screw threads 71 which are engaged by the exterior screw threads on the shank 74 of a brush holding member L which carries any suitable bunch of bristles O and has a head 73 to engage the inner face of the shuttle side wall.

The head of the brush member should entirely cover the shank hole such as 10 on the inner face of the side wall as shown by the dotted lines in Fig. 6, and if a head such as M is used, preferably its flat sides 36, 38 should be vertical so as to be parallel with the top and bottom faces of the shuttle as shown in Fig. 2 and its front and back ends 5 and 5 should be rounded or sloping so that no lint will get in hole 19 and will not scrape off on the edges of 36, as the thread unwinds spirally from the bobbin.

For both receiving member and brush holding member, I prefer to use a plastic or light metal such as aluminum or an alloy which will not upset the balance of the shuttle and, if the outer face of the shuttle wears down, the head of the receiving member will also wear down.

However, I may use metal for the receiving

member with interior threads and a plastic brush holding member of plastic such as shown at V in Fig. 11, with a head 90 and a shank 91 which has no exterior threads until the receiving member is screwed on to it cutting threads in 91 as it is turned.

The head of the receiving member and of the brush holding member may both be seated in a recess or one may be so seated and the other not so seated, but in any case, there should be a dead end hole with interior screw threads in the receiving member and a shank which has exterior screw threads engaging such interior screw threads when in use combined with a head into which is permanently fixed a bunch of bristles, such head and shank forming a brush holding member.

While preferably this brush holding member is made of a plastic such as polystyrene, it might be of any other suitable relatively soft plastic material, such for instance, as artificial rubber of the butadiene type forced in and around the bristles and then hardened or set.

I claim:

1. The combination with a weaving shuttle having an outlet eye, a bobbin chamber between its side walls and having a plurality of brush holes through its side walls, each brush hole having a countersunk cylindrical head recess in the outer face of a side wall and a smaller shank bore part with a smooth curved face extending through the side wall thereby leaving an annular shoulder; of a plurality of friction members, each including a plastic receiving member having a disk shaped head to fit the countersunk head recess and having a turning slot together with a tubular shank, smooth on the outside to fit the smaller shank bore part of the brush hole and provided with interior screw threads; a brush unit comprising a thermo-plastic bunch holding member having a shank with exterior screw threads to fit the interior threads of the receiving member tubular shank and a head to engage the inner face of the same side wall of the shuttle, such bunch holding member including a bunch of bristles of suitable plastic bent and extending into the bunch holding member and permanently fastened therein by being molded thereinto, extending diagonally inward towards the shuttle axis and outward towards the shuttle point which is proximate the shuttle eye whereby the heads of the receiving and bunch holding members can be clamped in place between the face of the annular shoulder of the brush hole and the inner face of a side wall.

2. The combination with a weaving shuttle having an outlet eye, a bobbin chamber between its side walls and having a plurality of brush holes through its side walls, each brush hole having a countersunk cylindrical head recess in the outer face of a side wall and a smaller shank bore part with a smooth curved face extending through the

side wall thereby leaving an annular shoulder; of a plurality of friction members, each including a receiving member having a disk shaped head to fit the countersunk head recess and having a turning slot together with a tubular shank, smooth on the outside to fit the smaller shank bore part of the brush hole and provided with interior screw threads; a brush unit comprising a bunch holding member having a shank with exterior screw threads to fit the interior threads of the receiving member tubular shank and a head to engage the inner face of the same side wall of the shuttle, such bunch holding member including a bunch of bristles extending into the bunch holding member and permanently fastened therein, extending diagonally inward towards the shuttle axis and outward towards the shuttle point which is proximate the shuttle eye.

3. The combination with a weaving shuttle having an outlet eye, a bobbin chamber between its side walls and having a plurality of brush holes through its side walls, each brush hole having a countersunk cylindrical head recess in the outer face of a side wall and a smaller shank bore part with a smooth curved face extending through the side wall thereby leaving an annular shoulder; of a plurality of friction members, each including a receiving member having a disk shaped head to fit the countersunk head recess and provided with interior screw threads; a brush unit comprising a bunch holding member having a shank with exterior screw threads to fit the interior threads of the receiving member disk shaped head, and a head to engage the inner face of the same side wall of the shuttle, such bunch holding member including a bunch of bristles extending into the bunch holding member and permanently fastened therein, extending diagonally inward towards the shuttle axis and outward towards the shuttle point which is proximate the shuttle eye.

4. For use in a weaving shuttle, a brush unit comprising a shank with exterior screw threads at one end and a head at the other, such brush unit including a bunch of bristles extending into the head at an angle with the shank and being inseparably fastened thereinto such head being of greater diameter than the shank and the face of the head which adjoins the shank being formed with corrugations.
